UNITED STATES PATENT OFFICE.

ELEAZER PARKINSON, OF YORKTON, SASKATCHEWAN, CANADA.

FARM GATE.

Application filed October 8, 1923. Serial No. 687,365.

To all whom it may concern:

Be it known that I, ELEAZER PARKINSON, a subject of the King of Great Britain, and resident of the town of Yorkton, in the 5 Province of Saskatchewan, Canada, have invented certain new and useful Improvements in Farm Gates, of which the following is the specification.

The invention relates to improvements in 10 farm gates and an object of the invention is to provide a simply constructed, light and strong gate which can be readily assembled and which is rigidly reinforced against twisting or warping.

15 A further object is to arrange the gate such that it can be easily tightened up from time to time as occasion requires and without necessitating the use of special tools.

20 With the above more important objects in view the invention consists essentially in the arrangement and construction of parts hereinafter more particularly described and later pointed out in the appended claims, 25 reference being had to the accompanying drawing in which:

Fig. 1 is a side view of the gate in closed position.

Fig. 2 is an enlarged detailed plan view 30 of the gate.

Fig. 3 is a sectional view at 3—3' Fig. 1.

Fig. 4 is a sectional view at 4—4' Fig. 1.

Fig. 5 is a face view of the latch.

In the drawing like characters of reference indicate corresponding parts in the several figures.

The gate, indicated generally by the reference numeral 1, is adapted to operate between the posts 2 and 3 being pivotally suspended from the post 2.

The gate is formed from the parts now described.

End uprights 4 and 5 are provided, these uprights being of equal length and being 45 provided with equi-spaced horizontal bolt openings 7 which receive similar adjusting bolts 8, the bolts having the heads at the outer sides of the uprights and their inner ends screw threaded and receiving adjusting nuts 9.

Towards the upper and lower ends the uprights are provided with openings which receive fastening bolts 10, these bolts being utilized to secure angularly disposed pairs 55 of intersection bars 11 and 12 to the uprights, there being a pair of brace bars at

each side of the uprights. The pairs of brace bars are held in an outwardly bowed position by a block 13 inserted between the pairs at their points of intersection and a 60 fastening bolt 14 passes through the brace bars and the block, holding these parts firmly together.

According to this arrangement the brace bars form a truss between the uprights. 65

On each of the bolts 8 I mount, between the nuts thereon and the upright, an anchoring strap 15, the strap being bent over the nut and having the two ends then brought together and provided with aligned openings 16. The opposing straps of the uprights are connected by wires 17, the wires having their ends passed through the openings 16 and thereafter tied.

The bolts associated with the upright 4 75 are utilized to fasten pivot members 18 and 19 to the uprights, the pivot members being really in the form of metal strips bent to span the upright and the brace bars and shaped to provide a socket 20, the sockets 80 being vertically aligned and located centrally at the outer side of the upright.

The gate is suspended from the post 2 by pintles or hangers 21 and 22 which have their upstanding ends adapted to pass into 85 the sockets. The swinging side of the gate is provided with an extending locking pin 23.

After the gate parts have been assembled one tightens up the nuts 9, this bringing 90 the wires into tension, which makes the whole structure very rigid.

The nuts can be tightened by turning the straps which are bent around the nuts so as to grip them and cause the same to rotate 95 upon the straps being turned. Of course this adjustment could also be effected by turning the heads of the bolts 8.

Whilst I have shown single wires connecting the straps this part of the gate 100 structure could be woven wire fencing if desired and without departing from the spirit of the invention.

It will be obvious from the above description that the gate is particularly light and 105 strong and will not warp or twist and that it can be readily tightened up from time to time as occasion demands.

The gate is held closed by a plate 24 fastened to the post 3 and provided with 110 an upturned notched flange 25, the notch being adapted to receive the locking pin of

the gate. A pivoted latch 26 is attached to the plate, the latch being held normally in the position best shown in Fig. 5, by the action of a spring 27. The lower end of the latch opposes the notch and is spaced therefrom, the arrangement being such that as the gate swings shut the latch is struck by the pin and moved with it sufficiently far to allow the pin to enter the notch, after 10 which time the latch returns to its normal position above the notch, thereby locking the pin in the notch.

To open the gate one simply shifts the latch sideways and raises the pin from the 15 notch.

What I claim as my invention is:

1. A gate comprising a pair of spaced end uprights, a pair of crossed stay bars located at each side of the uprights and 20 having the ends thereof connected to the upper and lower ends of the uprights by fastening bolts, means connecting the pairs of stay bars at their points of intersection, said means maintaining the stay bars outwardly bowed, spaced adjusting bolts passing through the uprights and provided with 25 adjusting nuts, straps mounted on the latter

bolts between the nuts and the uprights and having their ends bent around the nuts and brought together at the inner ends of the 30 latter bolts and tension wires connecting the opposing straps of the opposing uprights.

2. A gate comprising a pair of spaced end uprights, a pair of crossed stay bars 35 located at each side of the uprights and having the ends thereof connected to the upper and lower ends of the uprights by fastening bolts, means connecting the pairs of stay bars at their points of intersection, 40 said means maintaining the stay bars outwardly bowed, spaced tension wires extending between the uprights, adjustable means anchoring the ends of the wires to the uprights, and pivot supports attached to one 45 of the uprights by the bolts fastening the stay bars.

Signed at Yorkton, Canada, this 26th day of September, 1923.

ELEAZER PARKINSON.

In the presence of—

R. E. DAVIS,
A. J. GILBERT.
